UNITED STATES PATENT OFFICE.

JAMES WILLIS, OF CORNWALL, NEW YORK.

COUPLING-SLEEVE.

SPECIFICATION forming part of Letters Patent No. 415,759, dated November 26, 1889.

Application filed November 6, 1888. Serial No. 290,160. (No model.)

To all whom it may concern:

Be it known that I, JAMES WILLIS, a citizen of the United States, residing at Cornwall, in the county of Orange and State of New York, 5 have invented a new Coupling - Sleeve for Connecting the Tubes in the Construction of Tubular Arched Bridges, of which the following is the specification.

My invention relates to an improved coupling-sleeve for connecting the tubes of tubular arched bridges; and the objects of my improvements are, first, to strengthen the arch at the connection of the tubes by making the coupling-sleeve with an internal diametrical, 10 central, and vertical flat bar integral with it and occupying one-third of the length of the coupling-sleeve, with a hole pierced horizontally through the center of the bar and coupling-sleeve for the connecting-pin; second, to 15 preserve the proper position of the scarf'd ends of the abutting tubes, allowing the connecting-pin to pass evenly through all the parts; third, to permit a slight motion on the connecting-pin, which will compensate for 20 the expansion and contraction produced by the change of temperature. I attain these objects by the introduction of the vertical flat bar in the construction of the coupling-sleeve, as described above and illustrated in 25 the accompanying drawings, in which—

Figure 1 is a vertical longitudinal section through the center, showing the coupling-sleeve A B C D with the tubes E F G H and I K L M attached, and the pin-hole through

the center of the bar and the scarf's of the 35 tubes. Fig. 2 is a vertical lateral section through the center, showing the coupling-sleeve with the bar and the scarf's of the tubes setting against it and the section of the pin e passing through the whole. Fig. 3 40 is a horizontal longitudinal section at a right angle to Fig. 1, showing the coupling-sleeve A B C D with tubes attached, showing their scarf's a and b passing through the coupling-sleeve on the two sides of the bar c d, with 45 the pin e passing through the whole. Fig. 4 is the same section as Fig. 3, only the tubes and the pin are omitted, showing only the section of the sleeve and the pin-holes. Fig. 5 50 is the elevation of the coupling-sleeve and the tubes connected, as shown when finished and complete.

I am aware that coupling-sleeves have been used prior to my invention; but I am not aware that any coupling-sleeve has been used 55 or made with an integral vertical flat bar attached; but

What I do claim as my invention, and desire to secure by Letters Patent, is—

A coupling-sleeve having formed integral 60 with it an internal diametrical central flat bar forming a compact body in one piece, all substantially as set forth.

JAMES WILLIS.
